(57) **CLAIM**

What is claimed is the ornamental design for a microphone, as shown and described.

DESCRIPTION

FIG. 1 is a perspective view of a microphone;
FIG. 2 is a front view of the microphone;
FIG. 3 is a back view of the microphone;
FIG. 4 is a left side view of the microphone;
FIG. 5 is a right side view of the microphone;
FIG. 6 is a top view of the microphone;
FIG. 7 is a bottom view of the microphone; and,
FIG. 8 is an alternative perspective view of the microphone. The broken lines form no part of the claimed design.
